CLAIM

The ornamental design for a “reading blanket,” as shown.

DESCRIPTION

FIG. 1 is an elevational view of one side of a reading blanket according to the present invention;

FIG. 2 is an elevational view of the reverse side of the reading blanket shown in FIG. 1;

FIG. 3 is a bottom plan view of the reading blanket shown in FIG. 1;

FIG. 4 is an elevational view of a portion of a sleeve shown in FIG. 1;

FIG. 5 is an elevational view of the opposite side of the sleeve shown in FIG. 4; and,

FIG. 6 is a right-hand, perspective view of the sleeve shown in FIG. 5 with the upper portion bent back.
